AUTOMATIC CARRIAGE RETURN AND LINE FEED MECHANISM

Hilding A. Anderson, Lake Zurich, Ill., assignor to Klein-schmidt Laboratories, Inc., Deerfield, Ill., a corporation of Delaware

Application April 29, 1954, Serial No. 426,357

16 Claims. (Cl. 178—23)

This invention relates to carriage return and line feed mechanism for page printing telegraph and like receiving printing machines, and more particularly to improved means for automatically conditioning such mechanism for operation.

Most printing telegraph messages are transmitted from previously prepared message tapes. The tapes are usually prepared by typing perforators which consist of a keyboard associated with a tape printing and perforating mechanism. As the tape is a long strip the operator need pay no attention to line length as is the case when the printing is done on a page in tabulated form and messages recorded in this way are only receivable on other tape printing equipment. Page printers are often used for receiving messages and as the standard line is 72 spaces long, signals for carriage return and line feed must be sent at the proper time.

Some perforators have end of line indicators which inform the operator that the characters perforated will fill a line on the page and the operator can insert the signals necessary for carriage return and line feed operations of page printing receivers, but even with this improvement an operator sometimes fails to insert these signals, which omission causes all page printing telegraph machines in the line to lose the rest of the message.

Page printing telegraph machines are made with automatic carriage return mechanism but the majority of these have the disadvantage of overprinting the carried over character on the next printed line resulting in loss of the carried over character plus the over printed character. This is not too serious when the lost characters are alphabetical letters of a message. In most cases the lost letters may be interpolated from the arrangement of the rest of the letters of the word or by the meaning of the sentence in which the word occurs but, when the lost characters are numerals or letters of a code message, interpolation becomes more difficult and quite often impossible.

Among the prior art efforts toward a solution to the problem of overprinting characters on the next line has been to provide a mechanism automatically initiating a carriage return and line space function whenever the carriage has moved to within a predetermined distance from the end of a line and a non-printing function signal is received. Such a mechanism is intended to prevent overprinting on the next line by returning the carriage to its starting position within the time period required to perform one character printing operation, so that if the carriage return and line shift functions are initiated by receipt of a non-printing function signal, the carriage will have completed its return before the next signal is received. Mechanisms of this type do not present a completely satisfactory solution to the problem because, if no non-printing signal is received within the predetermined distance from the end of a line, overprinting at the end of the line will result until a non-printing function

2

signal is received and because the equal time periods for performing each function cause the maximum rate of time for recording of characters to be fixed by the time period required to safely accomplish a carriage return function.

5 If carriage return time is decreased past a certain value to increase character receiving rate, the resultant jarring by the carriage increases the wear and the frequency of repairs and adjustments.

This invention is independent of carriage return speed 10 or receipt of specific types of signals. The recording mechanism operates in a normal manner during the recording of an entire line of characters and the automatic carriage return and line shift functions are initiated when the carriage reaches the end of a line by receipt of any 15 type of signal, and if, during the carriage return, a character printing signal is received, the line shift will automatically function to present a clear surface for the next line and assure that the characters appear in their proper sequence from top to bottom of the page. Thus 20 the present invention eliminates overprinting of characters at the end of a line and on succeeding lines regardless of the ratio between character printing time periods and carriage return time period.

It is the primary object of this invention to overcome 25 the above described difficulties by providing automatic carriage return mechanism coupled with automatic line feed mechanism so that characters are never lost by piling up at the end of a line or over printing on the next line.

30 It is another object of the invention to provide means in a telegraph page printer to automatically enable the line space mechanism and carriage return mechanism to function on receipt of any signal by the signal receiving mechanism after the carriage has moved to the end of a line.

35 It is a still further object of this invention to provide means in a telegraph printer whereby if a character is printed during return movement of the carriage, the line shift mechanism will automatically function to shift 40 the recording medium so the next line of characters will be recorded on a fresh surface clear of previously recorded characters.

These and other objects of the invention will become 45 apparent from a reading of the following description of a representative embodiment of the invention; the accompanying drawings, and the appended claims.

In the drawings:

Figure 1 is a perspective view of the mechanism of this invention viewed from the rear of a machine as disclosed 50 in Kleinschmidt patent application S. N. 241,916, filed August 15, 1951, now Patent No. 2,773,931;

Figure 2A and 2B are detailed views of the carriage return selecting mechanism; and

Figure 3 is a representative telegraph message as printed 55 by a machine of the type disclosed in Kleinschmidt Patent No. 2,773,931 incorporating this invention.

The reference character 10 indicates a portion of tele-typewriter typebar carriage as described in Kleinschmidt Patent No. 2,773,931. Specifically, the part 10 is a journal for the type selecting arm 12 which may be rotated to any of 32 selectable positions by the meshed helical gears 14 and 16. The gear 16 slides on the square shaft 18 which is rotatably connected to a tele-typewriter selecting mechanism as disclosed in the above mentioned Kleinschmidt Patent No. 2,773,931. The part 10, hereinafter to be referred to as the carriage, is moved to the left, Figure 1, an amount equal to one letter space each time a printed character is selected. Carriage 10 will return to an extreme right hand position, its first recording position, any time a carriage return signal is received by the selecting mechanism,

Mounted on a boss 11 at the top of carriage 10 are two adjustable stops 20 and 22. These stops 20 and 22 are flat plates with respective slots 24 and 26 running lengthwise. They are suitably fastened on boss 11 by means such as screws 28 and 30 passing through slots 24 and 26. This enables stop 22 to be adjustably positioned to strike the end 34 of the lever 32 when the carriage 10 moves to its 73rd type position and will set in motion the automatic carriage return mechanism which will now be described.

Lever 32, mounted on the left side of the frame of the machine, as viewed from the rear, is pivoted at 35 and has an arm 36 extending toward the rear of the machine. The end of arm 36 is pivotally connected by rivet 38 to a link connector 40 screw-threaded to receive the threaded end 41 of a rod 42.

The right hand portion of rod 42 passes through a sleeve 44 which has attached to its left end a latch member 46 including a projection 47 and at its right end an arm 48. Sleeve 44 may be axially adjusted to a desired position on rod 42 and securely fastened by means such as set screw 45. A compression coil spring 50 butts against arm 48 and against a bracket of the frame (not shown) to bias the connecting rod 42 toward the left and to impart a clockwise movement, as viewed from above, to the lever 32.

Two permutation code segments 52 and 54 may be seen at the extreme right side of the drawing. These are two of the five segments of the selecting mechanism disclosed in Kleinschmidt Patent No. 2,773,931 hereinbefore cited. As viewed from the right of Figure 1, the segment 52 has been turned counterclockwise and indicates a "space" or no-current condition of the signalling code, while the segment 54 is in the "mark" or current position.

For a clear understanding of the mechanism comprising this invention it is necessary to briefly describe how the teletypewriter performs its carriage return and line feed operations upon receiving those particular coded signals. Lying alongside the coded segments 52 and 54 are two drop-in levers 56 and 58. Lever 56 is allocated to the line feed operation and lever 58 to the carriage return. Reference may be had to Figure 2A for specific details of this description. As viewed in the drawing, the front of the levers 56 and 58 have notches 60 and 62 at about their mid-sections and the inner edge of these notches pivot against an edge of a retaining comb 64 (indicated in Figure 1 by a heavy line). To the left of notches 60 and 62 are recesses 68 and 69 which are spaced to receive the ends of compression coil springs 70 and 71 the opposite ends of which are held by projections 72 and 73 of retaining comb 64. Thus it can be seen that drop-in levers 56 and 58 have a counter-clockwise bias which holds their right ends against code segments 52 and 54.

Pivoted journalled on the shaft 74 is lever 76 (allocated to the line feed operation) and 78 (to the carriage return operation). The lever 78 is mounted so that its projection 80 will engage the end of the drop-in lever 58 when the latter is in its normal or counter-clockwise position (shown by the phantom line of illustration Figure 2A). The lever 76 will engage the end of the drop-in lever 56 when it is in its normal position. The lever 78 has a lower leg 81 on the end of which is a rounded cam follower 82. A rearwardly projecting arm 84 of lever 78 has a spring 86 attached at 87 and to a post (not shown) of the machine frame. Spring 86 imparts a counter-clockwise bias to lever 78 about shaft 74. The end of arm 84 carries a post 88 attached to a vertical rod 90 by means of an eye 92. An eye 94 at the opposite end of the rod 90 is mounted on a post 96 projecting from an arm of a bell crank lever 98. The bell crank lever 98 is pivoted on a stationary part of the machine at 100 and its depending leg 102 has pivotally attached a link connector 104 to hold a rod 106 which is associated with a clutch to operate the carriage return mechanism. The cam follower 82 on lever 78 rides

on a cam 108 which is mounted on the function shaft 110 which makes one-half a revolution each time the machine receives a signal group indicative of a printed character or function. Also carried on shaft 110 are cams 112 and 114 associated with the line feed mechanism.

10 The lever 76 is similar to lever 78; its forwardly extending arm 77 engages the end of the drop-in lever 56 (indicated by phantom lines in Figure 1). A lower section 79 of arm 77 acts as a cammed end surface 117 to press laterally on a finger 118 on a lever 120 to press lever 120 laterally to the left. A spring 121 is connected to a central portion of lever 120 and to the frame (not shown) to bias lever 120 to the right. The cam follower 116 of lever 76 rides on cam 112 on function shaft 110. The vertical lever 120 is pivoted to an arm of a bell crank 124 at 122. Pivot 122 has enough play to allow for a slight sideways movement of the lower end of the lever 120. This lower end of the lever 120 has an arm follower roller 126 cooperatively engageable with cam 114 when lever 120 is moved sideways into alignment therewith. The bell crank 124 is pivoted at 128 to the frame, and has an upwardly extending arm 130 pivoted to a link 132 of the line feed mechanism. A spring 134 attached to a rear projection 135 of bell crank 124 biases the crank clockwise.

Operation of carriage return mechanism

When code segments 52 and 54, along with the other three that make up the complete permutation mechanism, are positioned in clockwise and counterclockwise directions, resulting from the reception of a group of signals coded for the carriage return, there will be a notch in each segment underneath the end of the drop-in lever 58 (Figure 2A). This lever 58, biased by spring 71, will pivot on the edge of comb 64 and turn in a counter-clockwise direction. The left end of the lever 58 will swing outwardly thus disengaging the end of the arm 80 as seen in solid lines of Figure 2A. The function shaft 110 then starts to rotate and cam follower 82 will drop off the high part of the cam 108, allowing a sudden counter-clockwise movement to the lever 78 through the biasing force of spring 86. Rod 92 will thus be pulled up and will turn bell crank 98 counter-clockwise resulting in an abrupt displacement of rod 106 to the right. This will activate the clutch mechanism to return carriage 10 to the right side of the machine.

The line feed mechanism works in a similar manner to the carriage return mechanism; when the drop-in lever 56 is turned counter-clockwise due to an alignment of notches 50 indicative of a line feed group of signals, end 77 of lever 76 will be disengaged from the drop-in lever 56 and, when the function shaft 110 revolves, the follower 116 will drop off, allowing a sudden counter-clockwise movement of lever 76 due to the biasing force of spring 141. Dropping of arm 77 will cause section 79 to act on cam surface 117 of finger 118 to move lever 120 to the left against the bias of spring 121 thereby positioning the roller 126 at the bottom of the lever 120 to the left and on the low part of cam 114. The continued revolving of the function shaft 110 will cause the cam lobe 115 to press down on the roller 126 causing lever 120 to move down and rotate bell crank lever 124 counter-clockwise to pull link 132 to the left. Associated with link 132 is a pawl and ratchet (not shown) for turning the paper feeding rollers for feeding a recording medium such as paper.

To complete the mechanism required for the automatic carriage return and line feed features a lever 138 is situated at the right of the space which is traversed by carriage 10. Lever 138 is pivoted at 140 to a stationary part of the machine and at the extreme right end has an upturned tip 136. The other end 142 of lever 138 extends downwardly to engage a tip 146 of a latch trigger 144 pivoted to the stationary machine frame at 147. Trigger 144 has an arm 148 extending to the right having a spring 145 attached at its midpoint to bias the trigger in a

clockwise direction about pivot 147. The arm 148 has a notch 150 at its outer end to engage projection 47 of latch member 46 under certain conditions to be described.

Operation of automatic carriage return and line feed

When the carriage 10 reaches the 73rd character space at the left of the machine the character for that position is printed and the stop 22 pushes the end 34 of lever 32 to the left. The turning of lever 32 pushes rod 42 to the right and moves the arm 48 to the right. Arm 48 engages notches 57 and 59 of the drop-in levers 56 and 58 and this right-ward movement of the arm 48 will slide the two drop-in levers 56 and 58 to the right (illustration Figure 2B). When the lower drop-in lever 58 is moved to the right the left end will disengage arm 80 of lever 78 allowing rotation of lever 78 and resulting in the herein-before described sequence of operations associated with the carriage return mechanism. Similarly the end of the drop-in lever 56 will disengage arm 77 of lever 76 and the previously described line feed operation will take place. To assure operation, the rod 42 is latched in its right hand position as now described. When rod 42 has been pushed to the right to set in motion the above sequence of operations latch member 46 moves to the right causing finger 47 to fall under notch 150 of the trigger 144. This notched end of the trigger will then drop down through the bias of spring 145 to hold latch 46, rod 42 and the arm 48 in their right hand positions.

When carriage 10 has returned to the right to the beginning of a line the adjustable stop 20 on top of the carriage will strike the end 136 of lever 138 to move the opposite end 142 to the left. End 142 strikes the shoulder 146 of trigger 144 to turn the trigger 144 counter-clockwise raising notch 150 out of engagement with latch 46. The rod 42 will then be moved back to the left by spring 50 and drop-in levers 56 and 58 will be shifted back to the left by arm 48 and positioned to engage the ends of levers 77 and 80 which, during the sequence of operations, have been restored by the cams 110 and 108 to their up positions. The machine is now conditioned to repeat the automatic cycle when the carriage again moves to the 73rd space.

As the machine of Kleinschmidt Patent No. 2,773,931, to which this specific embodiment has been adapted, requires approximately three times as long to return the carriage as to print a character, two character signals may be received during the carriage return movement. The automatic latch feature hereinbefore described, maintains the drop-in levers in their function transmitting positions throughout the carriage return movement, therefore each time a printing character signal is received during the carriage return movement, a character is printed and the line feed mechanism operated to advance the paper feed rollers and printing stock one line space. This feature of line feed during carriage return prevents overprinting of characters with the consequent loss of intelligence.

Having reference to Figure 3, the first line 152 and second line 154 of type have been printed in the normal manner with two carriage return signals and a line feed signal following the numeral 8. It is to be understood that a single carriage return and line feed signal is sufficient to start a new line when the machine is printing from a manually manipulated keyboard but when the printer is operating from a previously prepared message tape there is no pause between any of the successive signals and as hereinabove stated the carriage takes nearly three character periods to return, so a sufficient number of signals must be given for this operation.

The third line 156 of Figure 3 has been printed from signals received from a message tape wherein no carriage return or line feed signals have been interposed at the end of the line. When the carriage moved to the position to print the numeral 8, it conditioned the herein-disclosed automatic carriage return and line feed mecha-

nism and upon receiving the signal for the numeral 9 the platen fed a line and the carriage started to return. The numeral 9 was then printed in the position shown by the reference character 158. Immediately after the 9 was printed the signal for 0 was received, again the platen was line fed and the 0 was printed in the position shown at 160. After the 0 was printed a character space signal was received, again the platen was line fed and the carriage completed its travel to the start of the line. If the latter signal had been one resulting in a printed character, the printing of that character would have occurred at the beginning of line 162. The new line 162 was then printed.

It can be seen from Figure 3 that the numerals 9 and 0 are not lost by overprinting as would be the case if line 162 had not been dropped three spaces, and by reading from right to left the intelligence of the message is retained.

It will be understood that the mechanism disclosed in the foregoing description provides an effective and desirable solution to the problem of receiving tape fed messages on a page printing receiver without incurring either overprinting of characters at the end of a line, should no carriage return signal be transmitted, or overprinting during the carriage return movement with resultant loss of intelligence of continuity in a message. This is accomplished by incorporating an automatic carriage return and line feed function at the completion of a line of printed characters and further incorporating a line feed function each time a character is printed during a carriage return movement.

This invention will result in a printed message where all printed characters will be intelligible and the continuity of a message is not broken by overprinted characters or improperly spaced carriage return and line feed transmitting signals.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a telegraph machine: a selector mechanism adapted to convert received electrical signals into mechanical movement; a recording medium; a movable carriage; means carried by said carriage and controlled by said selector mechanism to record characters upon said medium in accordance with the received signals; means for normally moving said carriage one character space for each recording operation; a first means responsive to a specific received signal for returning said carriage to its starting position; a second means responsive to a different specific received signal for advancing said recording medium to start a new line; mechanical initiating means for enabling said first means and second means to respond to any received signal between the time the carriage reaches an end of line position and when it reaches a start of line position.

2. A telegraph machine as defined in claim 1, wherein said initiating means is so located that enabling of said carriage return means and said recording medium advancing means is effected by said movable carriage when the latter reaches a predetermined position in its character spacing direction.

3. A telegraph machine as defined in claim 2, wherein means are provided so that when said recording medium advancing means is enabled by said mechanical means it advances a line each time any signal is received during the period of mechanically initiated return of said carriage.

4. A telegraph machine as defined in claim 1, wherein

said selector mechanism includes first elements responsive to said specific received signals and second elements responsive to said different specific received signals, said first and second elements being also responsive to said mechanical initiating means.

5. A telegraph machine as defined in claim 4, wherein said selecting mechanism includes a group of notched permutation members, and in which said first element is pivotable into aligned notches of said permutation members as a result of receiving said specific signal, and in which said second element is pivotable into other aligned notches of said permutation members as a result of receiving said different specific signal, pivoting of said first and second elements causing said carriage return and line advancing means to operate, and mechanical means adapted to be actuated by said movable carriage to reposition said first and second elements to cause said carriage return and line advancing means to operate irrespective of specific electrical signalling conditions.

6. A telegraph machine as defined in claim 5, including means to latch said first and second elements in their new positions and means to return said first and second elements to their normal positions when said carriage has returned to the start of a line.

7. A telegraph machine as defined in claim 6, wherein said latching means is caused to be locked by said carriage when the latter is in its last character position of a line and wherein said latching means is caused to be unlocked when said carriage is in its start of line position.

8. A telegraph printing machine comprising: a frame; recording means; a carriage movably mounted on said frame; means for moving said carriage one character space for each recording operation; means including code segments for receiving and converting character and function indicative electric signals to coded predetermined permutative settings of segments; means controlled by said coded segments and said movable carriage and including elements engaging and responsive to specific code settings of said segments to advance the recording means one line space and to return the carriage to the starting position of a line; mechanically actuated means carried on said frame, cooperating with said elements and operating therethrough to return said carriage and to shift said recording means one line independently of a carriage return signal.

9. In a printing telegraph machine: a recording medium feeding roller; a movable type bar carriage; line space mechanism to advance said feed roller; a carriage return mechanism, a character space mechanism; electric signal responsive means including a group of selector members and a group of levers adapted to coact with said selector members and co-acting with said line space, carriage return, and character space mechanisms to selectively enable said mechanisms to perform their specific functions according to a received electric signal; mechanical means actuated by said carriage at one limit of its path of movement and interconnected with the one of said levers co-acting with said line space mechanism and with the one of said levers co-acting with said carriage return mechanism to mechanically shift such two levers independently of a received electric signal to enable said line space mechanism and said carriage return mechanism to function upon receipt of any signal received by the signal responsive means, said mechanical means including a latching means to maintain such two levers in their shifted positions until the carriage is returned to its opposite limit position.

10. An automatic line feed and carriage return mechanism for a telegraph printer including an electric signal actuated line feed and carriage return mechanism and a movable carriage disposed in a frame comprising: engaging means carried by said frame and adapted to be moved from a first position to a second position by said carriage moving past a predetermined position, to engage said signal actuated line feed and carriage return mechanism to mechanically enable said mechanism to be operated to

7
8

perform a line feed and carriage return function upon receipt of any signal by said signal receiving mechanism between the time that said carriage moves past the predetermined position and is returned to its start position.

5. 11. An automatic line feed and carriage return mechanism, as set forth in claim 10, further comprising: latching means co-acting with and holding said engaging means, as positioned by said carriage moving past a predetermined position, until said carriage has been returned to a line start position; whereby any signal received during the carriage return movement will result in a line feed operation.

15 12. In an automatic line feed and carriage return mechanism as set forth in claim 11: latch release means co-operating with said latching means and actuated by said carriage upon its return to the line start position to unlatch said engaging means; and means connected to and biasing said engaging means to the said first position.

20 13. In combination with a signal actuated receiver, a telegraph printer including a signal actuated line space and carriage return mechanism and a movable carriage disposed in a frame, means for effecting automatic actuation of said line space and carriage return mechanisms comprising means disposed on said printer in a normal, inoperative position and adapted to be repositioned by said carriage when the carriage moves past a predetermined location to engage said signal actuated line feed and carriage return mechanism to mechanically enable said mechanism to be operated to perform a line feed and carriage return function upon receipt of every subsequent signal by said signal receiving mechanism between the time the carriage moves past the afore-said predetermined location and the end of the carriage return movement.

25 14. In a telegraph printing machine including a type carriage and a platen carriage, one movable with respect to the other: a selectively settable permutation device comprising a plurality of selectively shiftable elements, a carriage return means rendered operative by one of said elements in its shifted position, a line feed means rendered operative by a second one of said elements in its shifted position, and means automatically operable upon the movable carriage reaching the end of a line position to shift said one and said second one of said elements independently of said permutation device to render both said carriage return and line feed means simultaneously operative upon every selective setting of said permutation device during the period from the time said movable carriage reaches the end of a line position until it has been returned to the start of a line position.

30 15. A telegraph printing machine comprising: a movable carriage, a selectively settable permutation device having a plurality of setting combinations corresponding to characters and machine functions, a first means responsive to one of said setting combinations for accomplishing a carriage return function, a second means responsive to a second of said setting combinations for accomplishing a line feed function, and a third means rendered operable by said carriage reaching the end of a line for enabling said first and second means to accomplish carriage return and line feed function for every selective setting of said permutation device occurring during the period from the time said movable carriage reaches the end of a line position until it has been returned to the start of a line position.

35 16. In a printing telegraph machine operated in response to coded signal conditions and adapted to record characters in transverse lines on a record medium: a carriage movable for character spacing, means for feeding said record medium in steps for line spacing, means for returning said carriage to its start-of-line position, and means rendered effective when said carriage reaches its end-of-line position and remaining effective until said carriage reaches its start-of-line position for causing said

carriage return means and said feeding means to be operated incident to any coded signal condition to return said carriage to its start-of-line position and assure that each character printed after the carriage reaches its end-of-line position and during the carriage return will not be overprinted by a succeeding line of characters.
